UNITED STATES PATENT OFFICE.

CHARLES SANFORD DIKEMAN, OF NEWBURYPORT, MASS., ASSIGNOR TO
THE TOWLE MANUFACTURING COMPANY, OF SAME PLACE.

DESIGN FOR A HANDLE FOR SPOONS OR FORKS.

SPECIFICATION forming part of Design No. 15,047, dated June 10, 1884.

Application filed April 23, 1884. Term of patent 7 years.

To all whom it may concern.

Be it known that I, CHARLES SANFORD DIKEMAN, a citizen of the United States, residing at Newburyport, in the county of Essex, of the Commonwealth of Massachusetts, have invented and produced a new and original Design for the Handle of a Spoon or a Fork; and I do hereby declare the same to be described in the following specification and represented in the accompanying drawing, which is a top view, on an enlarged scale, of a spoon having upon its handle the said design.

In the said drawing the design is shown as in four sections, (marked A, B, C, and D,) the first of such sections being next to the bowl E of the spoon. In each of the two extreme sections, A and D, there is in relief a tapering center, a, encompassed by a row, b, of beads, and a surrounding leaf, c. The section B represents a series, f, of flowers lapping on one

another. The section C tapers lengthwise, there being between it and the shield of the section D a series, d, of studs. The handle, tapering as shown, has to complete the design a raised fillet, e, extending about the edges of the three sections B, C, and D, all being substantially as represented.

I claim--

The ornamental design, substantially as set forth, for the handle of a spoon or other article, the said design consisting of the boundary-fillet e, the series of lapped flowers, the tapering centers a, the rows b of beads, the leaves c, and the studs d, as shown and described.

CHARLES SANFORD DIKEMAN.
